UNITED STATES PATENT OFFICE

HERMAN C. PRIEBE, OF BLUE ISLAND, ILLINOIS.

STEEL UNDERFRAME FOR CARS.

No. 861,391.

Specification of Letters Patent.

Patented July 30, 1907.

Application filed December 28, 1906. Serial No. 349,777.

To all whom it may concern:

Be it known that I, HERMAN C. PRIEBE, a citizen of the United States, residing at Blue Island, county of Cook, and State of Illinois, have invented certain new and useful Improvements in Steel Underframes for Cars, of which the following, taken in connection with the drawings, is a description.

My invention has for its object the production of a steel underframe for cars which shall be strong and durable, as well as simple and cheap in construction.

My invention is designed to be used on cars of various kinds, but is particularly applicable to refrigerator cars.

In the accompanying drawings I have illustrated what I now consider the preferred form of my construction, although the details of the same may be varied without departing from the spirit of my invention, and in these drawings

Figure 1 is a bottom plan view of the underframing of one end of a car; Fig. 2 is a view taken on line 2—2 of Fig. 1; Fig. 3 is a cross sectional view taken on line 3—3 of Fig. 1; Fig. 4 is a cross sectional view taken on line 4—4 of Fig. 1.

In the accompanying drawings I have shown the underframing of one end of a car and will confine my description thereto, it being understood that the opposite end is a duplicate of what is shown in the drawings.

A represents the longitudinal sills extending the length of the car, and A' is the end sill. The outer longitudinal sills are of the usual construction, but the center sill A² is disposed in the car frame with its widest dimension extending laterally as shown in Figs. 3 and 4. By this arrangement sufficient space is provided above the body bolster and said longitudinal sill, to allow for the truss angle hereinafter described.

B is the draw-bar; B' the yoke, B² the follower bars of the draft rigging, which in this instance forms no part of my invention.

B³ is the insulating material used in refrigerating cars of the ordinary construction.

C is the body bolster extending transversely of the longitudinal sills and c is the king-bolt passing through the center thereof. Channel irons C' are secured to each side of the center sill A and extend the entire

length of the car. c' are reinforcing angles secured to the channel irons C' to strengthen the same at the point where the angles C' take over the body bolster C.

A truss-angle D is secured to the channel irons C', and the reinforcing angles c', at each end of the car. This truss angle D extends over the body bolster C and beneath the needle beams D'. The needle-beams D' extend transversely of the longitudinal sills and are secured thereto by the bolts d. Upon each side of the needle beam D' are the bosses d'. A truss rod E is secured at each end thereof through the bosses d'. Each of the truss rods E extend upwardly toward the center thereof, as shown more clearly in Figs. 3 and 4, and pass over the longitudinal center sill A², securely binding the transverse and longitudinal sills. The longitudinal and lateral trusses, D and E secure the sills together and strengthen and equalize the weight and strain upon the entire underframe.

I claim:

1. In an underframe for cars the combination of the longitudinal and end sills, the body bolsters, the needle beams, truss rods secured to the outer ends of said needle-beams and taking over the longitudinal center sill of the car frame.

2. In an underframe for cars, the combination of the longitudinal and end sills, the body bolster, needle beams extending laterally of said longitudinal sills, a truss-angle extending beneath the center sill, over the body bolster and under the needle-beams, and truss rods secured to the needle-beams and taking over the center sills.

3. In an underframe for cars, the combination of the longitudinal and end sills, channel irons extending parallel with the center sill throughout its entire length, reinforcing angles secured thereto, the body bolster, and an angle truss, secured at each end thereof to the under side of the aforesaid center sill and to the angle plates.

4. In an underframe for cars the combination of the longitudinal and end sills, the center sill thereof having its widest dimension extending laterally at the frame, channel irons parallel with said center sill throughout its entire length, reinforcing angles secured thereto, and a truss angle secured at each end thereof to the aforesaid channel irons and center sill.

In testimony whereof, I have signed this specification in the presence of two subscribing witnesses.

HERMAN C. PRIEBE.

Witnesses:

JAMES P. CRANE,
WELLS GOODHUE.
